LOOM STOP MOTION

Verner Lindsjo, Stockholm, Sweden, assignor to
Draper Corporation, Hopedale, Mass., a corpora-
tion of Maine

Application January 8, 1935, Serial No. 881

7 Claims. (Cl. 139—370)

The present invention pertains to loom stop motions and has more particular reference to stop motions for actuating a shipper upon breakage or absence of filling.

5 The conventional loom, of the type to which my invention pertains, is provided with a filling fork and a filling fork slide which is normally stationary but which is positively moved upon detection by the fork of filling failure. Positive
10 connections from the slide serve to move the loom control member, or shipper, to loom stopping position upon movement of the slide. As previously constructed, the filling fork slide and shipper operating connections were positively
15 held in stopping position until after the loom had been turned forwardly at least one full pick after the stopping movement had taken place. The prior construction mentioned was not objectionable where the loom continued to run for
20 a pick or two after stopping movement of the shipper. However, modern looms are equipped with more efficient brakes, which bring the loom to a full stop within less than half a revolution from the time the shipper is actuated. When so
25 equipped, the loom will stop from the filling fork before the slide and shipper-operating connections have returned to loom-running position, with the result that the shipper can then be moved only part way on. With such constructions
30 it has been necessary in restarting the loom to first move the shipper part way "on" to start the loom running and then hold the shipper until the loom has turned over far enough to return the slide to normal position. Such operation is
35 awkward and even dangerous. Furthermore, it requires that the clutch and brake be set to operate when the shipper is near its off position, which objectionably delays their operation from the various stop motions.
40 I propose to overcome the aforementioned objections by providing for full movement of the shipper to loom-running position while the filling fork slide is in stopping position.

To the end mentioned, the invention provides, 45 in a loom having a shipper and a filling stop motion including a filling fork slide, connections from the slide for positively actuating the shipper and means for releasing such connections upon stopping movement of the slide. There is also
50 provided means for automatically restoring such connections subsequent to the restarting of the loom.

The preferred embodiment of the invention is
55 illustrated on the accompanying drawings, of
which:

Fig. 1 is a plan view of the stop motion comprising said preferred embodiment;

Fig. 2 is a sectional elevation taken approximately on line 2—2, Fig. 1;

Fig. 3 is a plan view showing certain parts of the stop motion as they appear just after the loom has stopped; and

Fig. 4 is a sectional view taken approximately on line 4—4, Fig. 3.

The loom shown on the drawings is conventional in many respects and it is accordingly but fragmentarily illustrated. Of the conventional construction there is shown a part of the frame including left hand loom side 1, and breast beam 2 at the front of the loom. There is also shown the lay 3 which reciprocates toward and from the front of the loom, a shuttle box 4 carried by the lay, a shuttle 5 adapted to be picked along the lay, a filling feeler 6, and feeler controlled parts 7 for effecting filling replenishment.

Breakage or absence of filling is detected by suitable means such as the conventional filling fork 8 which is pivotally mounted in the filling fork slide 9 for cooperation with the grate 10. When the fork is not tilted by filling it catches on a hook 11 on a means such as weft hammer 12 for positively moving the slide 9. The weft hammer, as is customary, reciprocates forwardly and rearwardly, making one complete reciprocation for each two picks of the loom, and is thus adapted to move the filling fork slide forwardly upon occurrence of filling failure.

The loom controls are represented on the drawings by a shipper 13 which may operate a clutch and brake, or the like, not shown. This shipper is moved forwardly to full-line position of Fig. 1 to start the loom, and is moved rearwardly to effect loom stoppage. The present invention provides a novel means for effecting stopping movement of the shipper from the filling fork 40 slide.

Connections from a filling fork slide for moving a shipper, as aforesaid, must be of a positive nature, at least to the extent of positively starting the shipper toward its off position. 45 Such connections as herein disclosed include a shipper knock-off lever 14 pivoted to the loom frame as at 15. One end of the knock-off lever engages in front of the shipper in position to move the latter toward off position when the lever 50 is moved clockwise, Fig. 1. A member 16 is connected to be positively moved forwardly by the slide 9. To this end it is conveniently constituted by an arm fixed to the rock shaft 17 and having a second arm 18 fixed thereto which second arm 55

extends in front of the slide. The member 16 is releasably but positively connected with the shipper knock-off lever, as by means of a dog 19 which is pivotally mounted on the member at 20 5 for movement both with the member and relative thereto. A depending shoulder 21 on the dog engages the knock-off lever for moving the latter.

The knock-off parts are shown, Fig. 3, in the 10 positions they occupy just after the loom has stopped. The shipper 13 is shown in its off position in full lines, while the on or loom-running position thereof is represented by dotted lines. The knock-off lever 14 is at the end of its 15 knock-off movement. It will be apparent that if the knock-off lever remained positively connected with the member 16 at this time, it would be impossible to move the shipper all the way on. I have provided means for releasing such 20 connections upon, or subsequent to, the knock-off part of the movement of the slide and lever, and simultaneously with the stopping of the loom.

The releasing of the connections between the 25 shipper may be effected in various ways. The particular connections shown on the drawings are released by the moving of the dog 19 out of engagement with the knock-off lever. To this end, there is provided cam means comprised of 30 a fixed cam part 22 and a downwardly and rearwardly inclined nose 23 on the dog 19. The part 22 may be fixed to the loom frame as shown. When the loom is running the parts occupy the 35 positions shown more clearly by Fig. 2. As the slide 9, member 16 and dog 19 move forwardly, the part 22 engages the nose 23 and thereby swings the dog 19 upwardly about its pivot 20. The parts are so constructed that the dog is not 40 lifted out of engagement with the knock-off lever until after the shipper has been moved, the releasing thus occurring subsequent to the knock-off movement proper.

After the connections have been released, as 45 just described, they occupy the positions shown by Figs. 3 and 4. It will be apparent that the lever 14 is free to be moved independently of the other parts (except for the light holding spring 24) and the shipper can accordingly be moved 50 all the way on even though the dog and slide have not returned rearwardly to loom running position. Such a construction eliminates the necessity for the awkward, dangerous method of manipulating the shipper above mentioned, and also permits the brake and clutch or the equivalent (not shown) to be set so as to be effective 55 when the shipper is close to its on position rather than near its off position. This latter feature permits the throw of the shipper to be reduced and also results in a quicker stop from 60 any of the stop motions with which the loom may be equipped.

There is also provided means for automatically 65 restoring the connection between the knock-off lever and the member 16 subsequent to the restarting of the loom. A spring 25 is fixed to the pivot 20 and bears against the dog 19 in such manner as to bias the latter downwardly. When the loom is first started the shipper moves the knock-off lever from the position of Figs. 3 and 4 to the position of Figs. 1 and 2, leaving the other parts in the stopping position of Figs. 3 and 4. After the loom has run about one pick the filling fork slide 9 and member 16 return rearwardly in the conventional manner, thereby moving the dog 19 rearwardly. Thereupon, the spring 25

forces the dog downwardly and thus restores the connection with the shipper knock-off lever.

Having fully disclosed the preferred embodiment of my invention, I claim:

1. In a loom stop motion, loom controls including a shipper, a side filling fork and filling fork slide, a weft hammer for positively moving said slide upon filling failure, a lever for moving said shipper to loom stopping position, a member connected to positively move said lever upon movement of said slide, means operable to disconnect said member from said lever subsequent to each stopping movement thereof, and means for restoring said connection subsequent to the restarting of the loom.

2. In a loom stop motion, a shipper knock-off lever, a side filling fork and slide, a member positively movable by said slide upon filling failure, a dog mounted for movement with said member, said dog being normally engaged with said lever for moving the latter upon movement of said slide, and means operable subsequent to each knock-off movement of said lever for disengaging said dog therefrom.

3. In a loom stop motion, a shipper knock-off lever, a side filling fork and slide, a member positively movable by said slide upon filling failure, a dog mounted on said member for movement therewith and relative thereto, said dog being normally engaged with said lever and operable when moving with said member to positively move said lever to knock-off position, and cam means operable to move said dog relative to said member out of engagement with said lever subsequent to each knock-off movement of the latter.

4. In a loom stop motion, a shipper knock-off lever, a side filling fork and slide, a member positively movable by said slide upon filling failure, a dog pivoted to said member for movement therewith and relative thereto, said dog having a shoulder engaging said lever whereby movement of said member moves said lever to knock-off position, cam means for pivoting said dog out of engagement with said lever subsequent to each knock-off movement of the latter, and means for returning said dog into engagement with said lever subsequent to the restarting of the loom.

5. In a loom stop motion, a shipper knock-off lever, a side filling fork and slide, a member positively movable by said slide upon filling failure, a dog mounted for movement with and relative to said member, said dog being normally engaged with said lever for moving the latter to knock-off position upon movement of said member, and a fixed cam part engaging said dog and causing the latter to move relative to said member out of engagement with said lever subsequent to each knock-off movement thereof.

6. In a loom stop motion, a shipper knock-off lever, a side filling fork and slide, a member positively movable by said slide upon filling failure, a dog pivoted to said member for movement therewith and relative thereto, said dog having a shoulder engaging said lever whereby movement of said member moves said lever to knock-off position, and a fixed cam part engaging said dog and causing the latter to pivot on said member to move said shoulder out of engagement with said lever at the end of each knock-off movement of the latter.

7. In a loom stop motion, loom controls in-

cluding a shipper, a filling fork slide, means for positively moving said slide upon filling failure, a member connected to and moving with said slide, a shipper knock-off lever having one end thereof in engagement with said shipper, a dog movable with said member and engaging the other end of said lever for imparting knock-off movement to the latter, and a fixed cam part engaging said dog and disengaging the same from said lever subsequent to each said knock-off movement.

5

VERNER LINDSJO.
